Application November 2, 1953, Serial No. 389,541

4 Claims. (Cl. 323—16)

The present invention relates to improved means and techniques for developing certain predetermined voltage variations and more specifically to a network involving unidirectional conducting elements, one or more of which is biased in such a manner that the voltage developed at the output of the network is not necessarily directly proportional to the magnitude of the voltage applied to the input of the network.

It is oftentimes desirable to develop an output voltage in a network which does not follow linearly the magnitude of the voltage applied to the input of the network, as for example in instrumenting computers of the character described and claimed in my copending patent application Serial No. 389,542, filed November 2, 1953, and assigned to the present assignee. Thus, it may, for example, be desirable to develop the voltage representative of the first quarter or 90° portion of a sine wave or to produce a voltage representative of other trigonometric variations such as, for example, the inverse secant of a particular angle. The means and techniques described herein are particularly applicable for those general purposes. It is understood that the means and techniques described herein are applicable to the generation of voltage variations which, when represented graphically, have a concave portion extending either in the downward direction or in the upward direction, or the output variations, represented graphically, may have a concave portion thereof extending downwardly as well as a concave portion extending upwardly.

It is therefore a general object of the present invention to provide improved means and techniques whereby the aforementioned indicated results may be obtained.

Another object of the present invention is to provide a network of this character which involves relatively few circuit elements.

Another object of the present invention is to provide improved apparatus of this character which is easily adjusted to obtain the desired voltage variations.

Another object of the present invention is to provide improved apparatus of this character, the operation of which is simple to understand thereby allowing quick adjustment.

The features of the present invention which are believed to be novel are set forth with particularity in the appended claims. This invention itself, both as to its organization and manner of operation, together with further objects and advantages thereof, may be best understood by reference to the following description taken in connection with the accompanying drawings in which:

Figure 1 illustrates a network embodying features of the present invention.

Figure 2 illustrates in graphical form the voltage variation obtained using the network illustrated in Figure 1.

Figure 3 illustrates another network embodying features of the present invention.

Figure 4 illustrates in graphical form the voltage variation obtained using the network illustrated in Figure 3.

Figure 1 illustrates a so-called biased diode function

generator which develops a voltage variation represented in Figure 2 by a curve concave in a downward direction.

For these purposes, a series of diodes 200, 201, 202, 203, 204, 205, 206, 207, 208 and 209, each having their anodes interconnected and their cathodes biased to different potentials, are used. The input voltage is supplied between the terminals 210, 212 and the output voltage appears across the terminals 214, 215, the terminals 210 and 215 being grounded. The anode of each of the diodes 10 is connected to the terminal 214, and terminal 214 is connected to terminal 212 through resistance 217. The voltage source 216 has its negative terminal grounded and its positive terminal is returned to ground through the resistance 218 and the gaseous voltage regulating tube 219 serving to maintain a potential of approximately 105 volts across the leads 220 and 222. A series of voltage dividing networks 230, 231, 232, 233, 234, 235, 236, 237, 238 and 239 are each connected between the leads 220 and 222 and each of such voltage dividing networks 20 has a corresponding adjusting tap 230A, 231A, 232A, 233A, 234A, 235A, 236A, 237A, 238A and 239A. These taps are connected through corresponding resistances 240, 241, 242, 243, 244, 245, 246, 247, 248 and 249 to corresponding cathodes of tubes 200, 201, 202, 203, 204, 205, 206, 207, 208 and 209. If desired, resistance 249 may have a value of zero ohms. The resistances have the values indicated in Figure 1 and, in this respect, the symbol K refers to one thousand ohms and the symbol M refers to one million ohms. It is thus observed that resistance 217 has a value of 100,000 ohms, resistance 240 has a value of 4.7 megohms, resistance 241 has a value of 2.2 megohms, resistance 242 has a value of 2.5 megohms, resistance 243 has a value of 820,000 ohms, etc.

It is observed that as the input voltage applied to terminals 210, 212 increases progressively, more and more of the diodes 200—209 are, in that order, rendered conductive so as to produce an increased voltage drop across resistance 217. However, the voltage drop across resistance 217 does not increase linearly but increases in a nonlinear manner as shown in Figure 2. The various resistances are so adjusted that the variation in output voltage appearing across the output terminals 214 and 215 has the desired variation, such variation in Figure 2 being the first 90° portion of a sine wave.

It is observed that in Figure 2 the abscissa of the curve which extends concave downwardly is the input voltage and the corresponding ordinates of the curve are corresponding output voltages appearing at the terminals 215, 214.

It is observed that the first diode 200, in the absence of any voltage applied to the input terminals 210, 212, is in a nonconducting condition and that a corresponding zero voltage appears at the output terminals 214, 215. The curve illustrated in Figure 2 is defined by essentially ten points, one point corresponding to each of the ten diodes shown in Figure 1. The general shape of the curve illustrated in Figure 2 may thus be altered by adjustment of the different points thereon, such adjustment being provided by the adjustable taps 230A—239A, both inclusive.

It is observed that each point on such curve represents the condition wherein the corresponding diode is rendered conductive. Thus, when the input voltage is raised from zero volts to a value of 15.64 volts, the first diode 200 is rendered conductive and such diode 200 remains in a conductive state for all values of input voltage above such value of 15.64 volts. When the diode 200 becomes conductive, a current flows through a path which includes the terminal 212, resistance 217, diode 200, resistance 240, tap 230A, a selected portion of the voltage dividing network 230, and the lead 220, and terminal 210. Such current flow through resistance 217 produces a corresponding voltage on the output terminal 214. Assuming that

70

the input voltage is then raised to a value of 30.90 volts, the second diode 201 is rendered conductive thereby to provide a second path for current flow, such second path including the common resistance 217.

When and as the input voltage is further increased, the remaining diodes, in turn, are rendered conductive thereby to provide additional paths for the current flow for increased voltage drop across resistance 217.

Figure 3 illustrates a network for obtaining a voltage variation which is concave in the upward direction instead of being concave in the downward direction. The network of Figure 3 includes the input terminals 300, 301 and the output terminals 302, 303, the terminals 301 and 303 being grounded. The resistance 305 is connected between terminals 300 and 302. A plurality 10 of unidirectional conducting devices in the form of hot cathode diodes, each has its cathode connected to the terminal 302. The anodes of such diodes 308, 309, 310 and 311 are each returned to ground through a corresponding network 318, 319, 320 and 321 comprising a 15 resistance serially connected with a voltage source. The negative terminal of each of such sources is grounded. The voltages of these sources are each different and normally maintain the diodes 308, 309, 310 and 311 in a conducting state, in the absence of a voltage applied to the input terminals 300, 301.

When the voltage applied to the terminals 300 and 301 is increased so that the terminal 300 becomes progressively more positive, the diodes 308, 309, 310 and 311 are progressively and in turn rendered nonconductive.

Thus, when the potential on the terminal 300 has the value corresponding to the voltage E_2 in Figure 4, the first diode 308 is rendered nonconductive; when the input voltage on the terminal 300 assumes the value represented by E_3 in Figure 4, the second diode 309 is rendered nonconductive; when the input voltage on terminal 300 is increased further to the value represented by E_4 in Figure 4, the third diode 310 is rendered nonconductive; and so forth. These values of voltages E_2 , E_3 and E_4 are adjustable by adjustment of the corresponding bias voltages 40 E_9 , E_{10} , E_{11} and E_{12} in the networks 318, 319, 320 and 321, respectively.

While the particular embodiments of the present invention have been shown and described, it will be obvious to those skilled in the art that changes and modifications may be made without departing from this invention in its broader aspects and, therefore, the aim in the append-

ed claims is to cover all such changes and modifications as fall within the true spirit and scope of this invention.

I claim:

1. A non-linear network of the character described comprising: a pair of input terminals and a pair of output terminals, a voltage dropping resistance connected between one of said input terminals and one of said output terminals, a plurality of diodes, each having one of its terminals connected to said one output terminal, a plurality of voltage sources of different magnitudes and each having one of its terminals connected to the other one of said input terminals and also to the other one of said output terminals, the other terminals of said voltage sources being connected to corresponding other terminals of said diodes so that the current which flows through a corresponding diode flows only through a corresponding voltage source.

2. A network as set forth in claim 1 in which said diodes are normally nonconducting but are rendered conducting, in turn, upon increase of voltage applying to said input terminals.

3. A network as set forth in claim 1 in which said diodes are normally conducting but are rendered nonconducting, in turn, upon increase of voltage to said input terminals.

4. A network as set forth in claim 1 in which said voltage sources comprise individual potentiometer resistances having taps connected individually to corresponding terminals of said diodes, a common power source having one of its terminals connected to said other output terminal and the other one of its terminals connected to an outside terminal of each of said particular resistances, the other outside terminals of said potentiometer resistances each being connected to said one input terminal.
